UNITED STATES PATENT OFFICE

JOHN J. KILBRIDE, OF SCOTCH PLAINS, NEW JERSEY

WINDOW-CLEANING DEVICE

Application filed October 12, 1928. Serial No. 312,179.

This invention relates to household accessories, and has particular reference to an improvement in window cleaning devices.

One of the principal objects of the present invention is to provide an improved window cleaning device which obviates the necessity of leaning out of the window when cleaning the outside surfaces of the window panes.

The invention further comprehends a window cleaning device which is so constructed as to facilitate the cleaning of the outside surface of the window pane of the inner sash without the necessity of partly operating upon the same from the lower end and from the upper end.

The invention further contemplates in a window cleaning device, a thin, flat pad of absorbent material adapted to contain a washing fluid, together with a handle member detachably connected therewith, and in which the pad and handle member are provided with interengageable locking means.

The invention further embodies in a window cleaning device, a handle member which includes a shank having an end provided with a locking notch spaced from its free terminal and adapted to be associated with a plurality of cleaning elements respectively provided with means designed to receive the end of the handle member and to cooperate with the locking notch, whereby said cleaning elements may be interchangeably associated with the handle member to perform their various functions.

Other objects of the invention reside in the comparative simplicity of construction and mode of use of the device, the economy with which it may be produced and the general efficiency derived therefrom.

With the above recited and other objects in view, reference is had to the following specification and accompanying drawings, in which there is exhibited an example or embodiment of the invention which is in no way intended as a limitation upon the scope of the appended claim, as it is to be clearly understood that variations and modifications which properly fall within the scope of said claim, may be resorted to when found expedient.

In the drawings:

Figure 1 is a perspective view illustrating the manner in which the device is employed for cleaning the outer surface of the window pane of the inner sash.

55

Figure 2 is a perspective view of the device on an enlarged scale.

Figure 3 is a similar fragmentary perspective view illustrating the rear of the cleaning pad and the manner in which the handle member is associated therewith.

60

Figure 4 is a fragmentary sectional view taken approximately on the line 4-4 of Figure 3.

Referring to the drawings by characters of reference, the device includes a handle member designated generally by the reference character 10 which is made up of a pair of slidably associated shank sections 11 and 12, the former having a hand grip 13 at one end thereof and the latter being provided with an angularly disposed arcuate terminal 14 at the same end, which terminal is designed to present a manipulating head for adjusting the length of the handle shank. The shank sections are slidably associated by means of sleeves 15 and 16, the former being secured to the shank section 12 while freely embracing the shank section 11. The latter sleeve 16 is secured to the shank section 11 and freely embraces the shank section 12. The shank section 12 is provided with an offset end 21 having a locking notch 22 spaced from the free terminal of said end.

75

The cleaning elements, which may vary in character according to their function, are designed for detachable association with the offset end 21 and the principal cleaning element consists of a sheet of absorbent material 23 which is stretched over a supporting frame constructed of wire mesh 24. The wire mesh frame has certain of its meshes or wires offset as at 25 to provide a series or plurality of aligned receiving loops through which the offset end 21 of the handle member is designed to be threaded until one of the loop snaps into the locking notch 22, thereby connecting and holding the cleaning element in place and against accidental displacement.

80

85

90

95

100

In use and operation, with the cleaning element and handle associated, it is obvious that the cleaning element may be impregnated with a cleaning fluid and the user by grasping the handle in the manner illustrated in Figure 1, may wash the outer surfaces of the window panes. Due to the fact that the cleaning element is in the nature of a thin, flat absorbent pad, it is obvious that the outer surface of the window pane of the inner sash may be washed completely by merely elevating the inner sash partway, as illustrated in Figure 1. Likewise, the outer surface of the window pane of the outer sash may be washed without the necessity of leaning out of the window.

What is claimed is:

A window cleaning device including a thin, flat cleaning element comprising a sheet of absorbent material and a mesh wire frame covered thereby formed with offset aligned portions defining receiving loops, and a handle member comprising a shank adapted to be trained through the receiving loops and having a notch spaced from its free terminal for locking engagement with one of the loops.
